SLIDE TRAY FOR A PHOTOGRAPHIC PROJECTOR

Stephen Blecher, Littleton, Colo., assignor to Honeywell
Inc., Minneapolis, Minn., a corporation of Delaware

Filed Dec. 23, 1968, Ser. No. 15,081

Term of patent 14 years

Int. Cl. D16—99

U.S. Cl. D61—1

FIG. 1

FIG. 3

FIG. 2

FIG. 4

FIG. 1 is a view showing one face of the slide tray;
FIG. 2 is a view showing the opposite face of the slide
tray from that shown in FIG. 1;

FIG. 3 is a view showing the side surface of the tray
and how it is associated with the face of the tray that is
shown in FIG. 2;

FIG. 4 is a view showing the side surface of the tray
and how it is associated with the face of the tray shown
in FIG. 1.

I claim:

The ornamental design for a slide tray for a photo-
graphic projector, substantially as shown.
